UNITED STATES PATENT OFFICE.

ROMANTA D. WOODFORD, OF CORTLAND, NEW YORK.

VEHICLE-SEAT LOCK.

SPECIFICATION forming part of Letters Patent No. 281,600, dated July 17, 1883.

Application filed February 15, 1883. (No model.)

To all whom it may concern:

Be it known that I, ROMANTA D. WOODFORD, a citizen of the United States, residing at Cortland, in the county of Cortland and State of New York, have invented certain new and useful Improvements in Automatic Wagon-on-Seat Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to wagon and other seats, and means for securing them to the bodies of wagons or other vehicles; and the novelty consists in the construction and arrangement of parts, as will be more fully hereinafter set forth, and specifically pointed out in the claims.

20 Dowel-pins, bolts, and guides, and other devices, have been before employed in this connection; but these constructions, so far as known to me, have lacked the quality of locking the seat against upward movement, as well as the wagon sides against lateral movement.

The object of this invention is to provide a locking attachment between the seat and body 30 or support which will prevent longitudinal, lateral, or vertical movement, will be automatically locked when placed in position, will be simple and cheap of construction, readily attached, durable and efficient in service, and 35 readily unlocked when it is desired to remove or change the position of the seat.

To these ends the invention consists in the mechanisms fully illustrated in the accompanying drawings, which form a part of this 40 specification, and in which—

Figure 1 is a perspective view of a wagon seat and body with my improved fastening device in position; Fig. 2, a transverse section of the same, and Fig. 3 a perspective view of 45 the three parts detached and slightly modified.

For convenience I will describe the device as applied to road-wagons or similar vehicles; but it is obvious that it may be employed in 50 other relations with equal efficiency and convenience without either departing from the principle or sacrificing the advantages of my

invention, the essential features of which will now be described.

Referring to the drawings, in which similar letters of reference indicate like parts in all the figures, A indicates the base-frame, having a longitudinal recess, a, adapted to receive the shank b of a hooked tongue, B, and a bridge, a', under which said tongue operates, 60 a spiral spring, C, serving to hold the tongue in constant contact with the frame A, except when the force of the springs is overcome. The tongue B is preferably pivoted or journaled in the head a² of the base-frame A by the 65 same means, a³, which assists to secure the device to the seat-standards, and the hook b' is inclined inward, as shown, to correspond with the engaging-surface d of the staple D. The spring C fits at one end neatly over a lug, b², 70 upon the tongue, and at the other upon a similar lug or teat, a⁴, formed upon the lower or inner side of the bridge a'.

The frame A and tongue B are secured by screws to the seat-standards, and the staple D 75 to the body sides of the vehicle. The side of the staple next to the joint is beveled, as shown at d', in order that the contracting beveled surface b³ of the tongue may ride up the same and automatically overcome the force of 80 the spring C when the seat is placed in position, and the frame A is provided with a projection, A', which, in the same operation, passes through the bridge formed by the staple D.

Dowel-pins and corresponding recesses may be provided between the bearings of the seat-standards and body sides, if desired; but these features are well known and form no essential part of this invention.

In the modification shown in Fig. 3 the tongue B has a cross-journal, which has a bearing in the frame A; but I prefer the construction wherein the tongue is pivoted upon the securing screw or bolt.

It will be observed that the staple D and frame A, having projection A', prevent the body sides from spreading or moving inward, while the hook, in connection with said staple, prevents the displacement of the seat vertically.

What I claim as new is—

1. As a means for securing a seat to its bearings, a base-plate secured to the seat and hav-

having a projection which operates under a staple to prevent lateral play, and a spring-tongue having a hook which engages the said staple upon its outer side, and pivoted by the same means which secures the base-plate to the seat, as set forth.

2. In combination with the frame or base-plate A, having projection A', head a², and bridge a', the tongue B, having hook b', bevelled surface b³, and pivoted by the securing-

screw a³, the spring C, and the staple D, having beveled surface d, all constructed and arranged to operate as and for the purposes set forth.

In testimony whereof I affix my signature in presence of two witnesses.

ROMANTA D. WOODFORD.
